UNITED STATES PATENT OFFICE.

GEARHART GANGELHOFF AND MICHAEL JORDAN, OF MINNEAPOLIS, MINNESOTA.

BED WITH RESILIENT SUPPORT FOR SPRING FRAMES.

Application filed June 11, 1925. Serial No. 36,337.

This invention relates to a bed structure, and particularly to such a structure in which the bed frame carries an auxiliary spring support for the bed spring frame. The present invention is an improvement upon that disclosed and claimed in our prior application, S. N. 742,808, filed October 10, 1924.

It is an object of this invention to provide a simple and efficient structure carried in the member extending between the side rails of the bed for resiliently supporting a bed spring frame.

It is more specifically an object of the invention to provide a bar, preferably an angle bar, spanning the side rails of the bed frame, which bar has a longitudinally extending recess cut therein preferably in a horizontally disposed flange thereof, one or more springs being disposed at each end of said recess having one end secured to the said bar at the ends of said recess, together with a bed spring frame supporting bracket disposed in said recess having the other ends of said springs secured to the opposite sides thereof.

These and other objects and advantages of the invention will be fully set forth in the following description made in connection with the accompanying drawings in which like reference characters refer to the same parts throughout the different views, and in which,

Fig. 1 is a plan view of one corner of a bed frame embodying the present invention;

Fig. 2 is a vertical section on the line 2—2 of Fig. 1, as indicated by the arrows; and

Fig. 3 is a vertical section on the line 3—3 of Fig. 2, as indicated by the arrows.

Referring to the drawings, a bed frame of common construction is disclosed comprising the end member 4 having an inwardly projecting lug 4^a in which is detachably carried one end of the side rail 5 of the bed frame, which side rail extends between the two end members of the bed frame, it being understood, of course, that there is a side rail 5 at each side of the bed frame. A bar 6 is provided adapted to extend between the side rails 5 adjacent one end of the bed and while the said bar may be variously formed, in the embodiment of the invention illustrated the same is shown as an angle bar having a horizontally dis-

posed flange 6^a. The vertical flange of said bar 6 is cut away adjacent one end and an adjustable extension plate 7 is secured to the horizontal flange by a headed and nutted bolt 8 extending through said plate 7 and through an elongated slot 6^d in the horizontal flange 6^a. The horizontal flange 6^a is also cut away adjacent the end of bar 6 to form a longitudinally extending recess in said flange. A smaller angle bar 6^b is bolted to the outer side of the vertical flange of bar 6 to reinforce the same. A pair of springs 9 shown as coiled tensile springs, are disposed adjacent each end of said recess and have one of their ends secured in apertures 6^c formed in the bar at each end of said recess. A bracket 10 is provided which forms the supporting bracket for a bed spring frame, which bed spring frame 75 comprises spaced rods 11 shown as tubular in form secured in the brackets 10, said brackets being secured at their ends to bars 12 extending transversely of the bed parallel to bar 6, said bars 12 being illustrated 80 as angle bars. The bracket 10 has a flat face fitting against the end side of the vertical flange of the angle bar 12 and has a pin 10^a extending through an aperture in said bar and is further secured to said bar by a headed and nutted bolt 13. A multiplicity of tensile coiled springs 14 are secured in spaced relation to the horizontal flange of bar 12 to which springs the spring fabric 15 of the bed spring frame is connected. 90 The bracket 10 has a flange 10^b projecting at each side at its bottom part, said flanges being disposed substantially in the plane of the horizontal flange 6^a and having secured thereto the adjacent ends of springs 9. 95

From the above description it is seen that the bed spring frame is supported by brackets 10 which are, in turn, supported by the springs 9 and the bar 6. There will, of course, be a bracket 10 adjacent each end of bar 6 and there will be one of the bars 6 adjacent each end of the bed. A simple and efficient auxiliary resilient support is thus provided for the bed spring frame, the spring 9 resiliently supporting the brackets 10 and acting to hold the same in proper position. The springs 9 are conveniently secured to the bar 6 and conveniently disposed in the recess formed in said bar. An extremely simple and efficient structure is thus provided. The plate 7 can be adjusted as desired so that the bar 6 can be used with

different widths of bed frames. The structure is easily and inexpensively produced and the same has been amply demonstrated in actual practice and found to be very successful and efficient, and is being commercially made.

It will, of course, be understood, that various changes may be made in the form, details, arrangement and proportions of the parts without departing from the scope of applicants' invention, which, generally stated, consists in a device capable of carrying out the objects above set forth, in the novel parts and combinations of parts disclosed and defined in the appended claims.

What is claimed is:

1. The combination with the longitudinally extending spaced members of a bed frame, of a bar spanning said members and supported thereby, said bar having a recess formed therein, a spring at each end of said recess and having one end secured to said bar at said end, and a bed spring frame having a supporting member disposed between and supported by said springs.

2. The combination with the longitudinally extending spaced members of a bed frame, of a bar spanning said members and supported thereby, said bar having a recess formed therein, a spring at each end of said recess and having one end secured to said bar at said end, and a bed spring frame having a supporting bracket secured thereto, said bracket having respectively secured at opposite sides thereof the other ends of said springs.

3. The combination with the longitudinally extending spaced members of a bed frame,

of a bar spanning said members and supported thereby, said bar having a recess formed therein, a bed spring frame supporting bracket disposed in said recess, and resilient supporting means for said bracket secured to said bar and disposed in said recess.

4. The combination with the longitudinally extending spaced members of a bed frame, of an angle bar spanning said members and having a substantially horizontally disposed flange cut away to form a recess extending longitudinally of said bar, a pair of coil springs at each end of said recess and secured at one of their ends to said bar at the end of said recess, a supporting bracket of a bed spring frame having flanges at each side respectively secured to the other ends of said pairs of springs and supported thereby.

5. A bar adapted to span the longitudinal side members of a bed frame formed with cut-out rectangular portions adjacent its ends, springs running longitudinally of said cut-out portions having one of their ends attached to said bar and a bracket holding a bed spring frame fitting within said cut-out portions, the other ends of said springs being connected to said bracket.

6. A bar adapted to span the spaced longitudinal side members of a bed frame and having a recess therein and resilient means extending substantially parallel to said bar across said recess and connected to said bar for supporting one of the side rails of a bed spring frame.

In testimony whereof we affix our signatures.

GEARHART GANGELHOFF.
MICHAEL JORDAN.
